Frank Briese

UNITED STATES PATENT OFFICE.

HENRY BRIESE, OF FAR ROCKAWAY, NEW YORK.

CULINARY VESSEL.

1,261,352.

Specification of Letters Patent.

Patented Apr. 2, 1918.

Application filed December 10, 1917. Serial No. 206,462.

To all whom it may concern:

Be it known that I, HENRY BRIESE, a citizen of the United States, and a resident of Far Rockaway, in the county of Queens and State of New York, have invented certain new and useful Improvements in Culinary Vessels, of which the following is a specification.

This invention relates to a culinary vessel, of novel construction, which is so constituted that the area of its heat receiving surface is greatly increased so that the time for boiling water or other liquids is correspondingly reduced.

15 In the accompanying drawing:

Figure 1 is a vertical central section of a culinary vessel embodying my invention, and Fig. 2, a bottom view thereof.

The body 1 of the vessel (which may be 20 of suitable configuration) is provided with a raised false bottom 2, from which depends a circumferential flange 3 that is inclosed by and concentric to body 1 and is connected at its lower end to such body by means of 25 a narrow annular bottom proper 4. In this way, there is formed at the bottom of the vessel, an annular circumferential channel 5, that communicates with the interior of the vessel, and incloses a circular heating 30 chamber, which is defined by the false bottom 2 and flange 3. Within this chamber are accommodated a plurality of tubes 6, the number and arrangement of which may be modified at pleasure. These tubes open

at the upper ends into the interior of vessel 35 1, through false bottom 2, which is correspondingly apertured.

The tubes are closed at their lower ends, and their length corresponds preferably, to that of flange 3, so that the tubes assist an 40 nular bottom 4 in sustaining the vessel upon the stove or other heat generator.

It will be seen that when the vessel is charged, the liquid will fill channel 5, tubes 6, and the body of the vessel, up to the level 45 desired. The heat supplied by the stove will rise within the space inclosed by flange 3, and thus heat channel 5 as well as the body of the tubes which traverse such space. Owing to the extensive heat-receiving surface 50 presented by the tubes within this space, in conjunction with the extensive heat-receiving surface presented by the annular channel, the liquid may thus be brought to a boiling point in considerably less time than 55 was heretofore generally required.

I claim:

A culinary vessel having a lower inner flange concentric with the body of the vessel and forming a lower annular channel, an 60 apertured raised bottom carried by said flange and forming a heating chamber that is encompassed by said channel, and a plurality of tubes that depend from said raised bottom, within said chamber and communicate with the interior of said vessel.

HENRY BRIESE.
